UNITED STATES PATENT OFFICE.

CHARLES M. BOWMAN, OF LEBANON, PENNSYLVANIA.

FIREPROOF BOOK.

SPECIFICATION forming part of Letters Patent No. 681,097, dated August 20, 1901.

Application filed March 22, 1900. Serial No. 9,797. (No model.)

To all whom it may concern:

Be it known that I, CHARLES M. BOWMAN, of Lebanon, in the county of Lebanon, and in the State of Pennsylvania, have invented certain new and useful Improvements in Fireproof Books; and I do hereby declare that the following is a full, clear, and exact description thereof, reference being had to the accompanying drawings, in which—

10 Figure 1 shows a perspective view of a book prepared in accordance with my invention; Fig. 2, a view of a transverse section of the book as closed; Fig. 3, a perspective view of my book provided with a protective slip-cover, and Fig. 4 a transverse section of such book as closed.

Letters of like name and kind refer to like parts in each of the figures.

The object of my invention has been to provide an improved fireproof book; and to this end my invention consists in the fireproofed book, as hereinafter described.

The special purpose of my invention has been to produce a book which when closed, as a book ordinarily is when laid or stored away and not in use, shall be capable of resisting the burning or charring of its pages by great heat or fire applied to or surrounding it.

30 As is well known, ledgers and other books, even when stored away in so-called "fireproof" safes, are apt to be burned or charred to a considerable depth inward from the edges of their pages if the safe is subjected to fire for any considerable time. Although the books may be protected, so that their pages are not actually consumed, this partial burning or charring, extending inward from the edges of the pages, often destroys or effaces the im-

40 portant figures or parts of the records extending along the outer edges of the pages, so that as good and valuable records the books are essentially destroyed or rendered valueless. In carrying out my invention, so as to prevent even this charring or burning of the edges or marginal portions of the pages of a

45 book, I apply to the edges or marginal portions of the pages fireproofing material, preferably silicate of soda or water-glass in solution. While I prefer the silicate of soda for this purpose, I desire it to be understood that I do not limit myself to the use of such ma-

terial, but contemplate using instead, when desired, silicate of potash, tungstate of soda, or other suitable fireproofing substance or compound. The fireproofing material can be applied to the edges or marginal portions of the pages either by a brush or by dipping the pages to a slight extent into a bath of the material in solution. The application is preferably so made that the fireproofing material or compound will effect the marginal portions of the pages extending inward a short distance from the extreme outer edges of the pages; but I do not limit myself to any particular extent of the fireproofed margin. Application of the fireproofing material simply to the extreme outer edges of the pages affords good protection against burning or charring inward of the pages when the book is closed tightly. A very narrow strip of fireproofed paper, being unable to burn itself, affords protection to the paper of the page within and beyond such strip, as it forms a good non-conductor of heat.

75 In Figs. 1 and 2 of the drawings is shown a book treated in accordance with my invention, A A designating the pages of the book, and B its cover. Each page has its outer edges or marginal portions treated with fireproofing material, as and in the manner set forth hereinbefore, so as to form around the page edges a narrow marginal strip of fireproofed material, as indicated at a a in the drawings, in which the fireproofed portion is 80 for clearness sake shown as shaded, though in practice the fireproofing solution or compound need not be such as to disolor the treated portion of the page. A thin solution of silicate of soda or potash, for instance, 85 would not when applied to the edge of an ordinary paper-book page materially change the same in appearance in any way.

In the drawings the treated portion a a of the book-pages is shown as extending inward a short distance on the page; but it will be understood that such portion may be made narrower or broader, if desired, without departure from my invention.

100 The cover B of the book I make of fireproof material—such, preferably, as cloth, millboard, or paper made of asbestos—having its exterior covered with leather or other desired material.

- In the drawings, *b b* designate the body or interior of the cover *B*, made of asbestos cloth, millboard, or paper, as above described, and *b'* designates the leather or other exterior covering. The construction of the cover is preferably such that the asbestos or other fireproof material thereof will when the book is closed be in close contact with the outer pages of the book, so as to protect the same from access of destructive heat or fire to the unfireproofed main portions of such pages.
- The back part of the cover *b'* should be so arranged as to be in close contact with the back or inner edges of the pages when the book is closed, so as to protect such edges from burning or charring by fire in contact with the back of the book. For insuring absolutely any danger of such charring or burning I contemplate also, where desired, treating the inner or back edges of the pages also with the same fireproofing material or compound as the other edges of the pages to form a narrow protecting line or margin of fireproofed paper along such inner or back edges, as indicated at *a'* in the drawings.
- Instead of making up the book-cover as described hereinbefore and shown in Figs. 1 and 2 of the drawings—that is, with an interior body of fireproof material and an exterior of leather or other covering—I contemplate having the body *C* of the cover made, as usual in books, of paper, board, leather, or other suitable material and then applying to such body a protecting slip-cover (shown at *D* in Figs. 3 and 4) made of fireproof material, preferably asbestos cloth or fabric, placed on and over the cover-body in the well-known way of applying slip-covers to books. Such fireproof protective slip-covers should not only extend over the outside of the cover-body, but over the inside faces of the cover-body flaps, so that when the book is closed it will be in close flat contact with the outer pages of the book.
- Books already made in the ordinary well-known ways and of the usual materials may be fireproofed in accordance with my invention by having the silicate of soda or other fireproofing material applied with a brush or otherwise to the edges of its pages, while the

covers can be protected and the protection of the outer pages can be secured by placing on the covers fireproof slip-covers of the kind just above described.

The treatment of books in accordance with my invention to protect their pages from charring or burning is exceedingly simple and cheap and has been found most efficient to prevent injury of a closed book by fire.

Books made and treated in accordance with my invention, if simply closed, as they would be usually when not in use, have been found to be capable of withstanding the action of fire and intense heat for a long time without burning or even charring of the edges of the pages, all of the records on such pages, even close up to the outer edges thereof, being kept uninjured, intact, and perfectly legible.

Having thus described my invention, what I claim is—

1. As an article of manufacture, a book having one or more of the outer edges only of its leaves made proof against injury by fire, substantially as and for the purpose described.

2. As an article of manufacture, a book having the outer edges only of its leaves treated to render them fireproof, substantially as and for the purpose described.

3. As an article of manufacture, a book having the outer edges only of its leaves rendered fireproof, and a cover having a layer of fireproof material to extend over and cover the outer leaves, when the book is closed, substantially as and for the purpose described.

4. As an article of manufacture, a book having the outer edges only of its leaves rendered fireproof, and a fireproof cover to cover the interior back edges of the leaves, and extend over and rest in close contact with the outer leaves of the book, when the latter is closed, substantially as and for the purpose described.

In testimony that I claim the foregoing I have hereunto set my hand this 17th day of March, A. D. 1900.

CHARLES M. BOWMAN.
